COMBINED ROTATABLE SIGN AND SUPPORT

Nicholas Louis Mezin, Jr., Rte. 1, Box 754H, Groton
Place, Escondido, Calif. 92025

Filed Oct. 3, 1968, Ser. No. 13,833

Term of patent 7 years

Int. Cl. D20—03

U.S. Cl. D96—12

FIG. 1

FIG. 3

FIG. 2

FIG. 1 is a top plan view of a combined rotatable sign and support sign showing my new design;

FIG. 2 is an elevational view taken from one side thereof and the other two sides of the rotatable sign being the same as the side shown, and

FIG. 3 is an enlarged sectional view taken on line 3—3 of FIG. 2.

I claim:

The ornamental design for a combined rotatable sign and support, substantially as shown and described.
